UNITED STATES PATENT OFFICE.

CHRIST ADLER, OF MILTON CENTRE, OHIO.

SPEED AND MOTION REGULATOR FOR MACHINES.

SPECIFICATION forming part of Letters Patent No. 267,818, dated November 21, 1882.

Application filed September 15, 1882. (No model.)

To all whom it may concern:

Be it known that I, CHRIST ADLER, of Milton Centre, in the county of Wood and State of Ohio, have invented a new and Improved 5 Speed and Motion Regulator for Machines, of which the following is a full, clear, and exact description.

The object of my invention is to provide a new and improved device for regulating the 10 speed and direction of motion in machinery.

Reference is to be had to the accompanying drawings, forming a part of this specification, in which similar letters of reference indicate corresponding parts in all the figures.

15 Figure 1 is a perspective view of my improved device for regulating the speed and direction in machinery. Fig. 2 is a longitudinal sectional elevation of the same. Fig. 3 is an end elevation of part of the same. Fig. 4 is 20 a plan view of the front end of the machine. Fig. 5 is a perspective view of a notched frame for holding the adjusting-lever in the desired place. Fig. 6 is a cross-sectional elevation of the shaft to which the motion is to be transmitted.

25 The shaft A, to which the power is to be transmitted, is journaled in the side pieces, B', of the frame B. The shaft C, from which the power is to be transmitted, is also journaled 30 in the side pieces, B', of the frame B, and on the same is mounted a belt-pulley, C', for the driving-belt C², and a belt-pulley, D, over which a belt, E, passes, which also passes over a pulley, F, on a vertical shaft, G, which is journaled in a U-shaped frame, H, the ends of 35 which are journaled on a shaft, A, journaled in the frame B, so that the frame H can rock on the shaft A. A spring, J, contained in the upper part of the frame H presses on a plate 40 attached to the upper end of the shaft G, and is held between the said plate and a plate attached to the lower end of an adjusting-screw, K, projecting from the top of the frame H, and provided with a handle, K'. A friction-wheel, 45 L, is rigidly mounted on the lower end of the shaft G, between the shanks of the frame H, which friction-wheel is provided in its lower flat surface with a concavity, a, at the middle. The plane of the friction-wheel L will be par- 50 allel with the longitudinal axis of the shaft A. On the shaft A the friction-wheel M is mounted,

the plane of which is at right angles to the shaft A, and the edge of which friction-wheel is in contact with the lower smooth surface of the friction-wheel L. A feather, b, on the 55 shaft A passes through a notch in the hub of the friction-wheel M, so that the said friction-wheel must rotate with the shaft A, but can slide longitudinally on the same. The hub M' of the wheel M is provided with an annular 60 groove, into which a fork, O, passes, the opposite end of which is adapted to slide on a rod, N, attached to the sides B' of the frame B, parallel with the shaft A. The free end of the fork O is connected by a wire, d, with the end 65 of an arm, P, of a vertical shaft, Q, journaled in a standard, R, on the end of the frame B, which arm P passes through a horizontal slot, P', in the end piece, B². The upper end of the shaft Q is provided with a handle, S, upon 70 which a locking-lever, S', is pivoted, the inner end of which passes through the handle S, and is adapted to catch on a notched segmental plate, T, secured on the upper end of the standard R. The frame H is connected with 75 the standard R, and is held in the desired position by means of a rod, U, and spring W, the tension of which spring can be adjusted by means of a double nut-frame, Y.

The operation is as follows: The shaft C is rotated by means of the belt C² from some suitable motor. The belt E is drawn taut by means of the spring W, the rod U, and the double nut-frame Y, and consequently will rotate the shaft G and the friction-wheel L mounted thereon. 80 The spring J presses the shaft G downward, and thus presses the surface of the friction-wheel L on the edge of the friction-wheel M. The spring J can be adjusted by means of the screw-rod K to exert a greater or less pressure 85 on the shaft G. As the friction-wheel L is rotated and is in contact with the friction-wheel M, the latter will also be rotated, and will in turn rotate the shaft A, to which the power is to be transmitted. If the edge of the wheel 90 M is in contact with the surface of the wheel L near the periphery, the wheel M will be rotated very rapidly; but as the wheel M is gradually moved toward the middle of the wheel L the speed decreases, and when the edge of 95 the wheel M is at the middle of the wheel L the motion of the shaft A ceases, as on account 100

of the concavity the wheels cannot come in contact, the pulley F preventing the spring J from forcing down the shaft G sufficiently to cause contact. Thus, by moving the edge of 5 the wheel M to and from the periphery of the wheel L the speed of the shaft A can be increased or decreased gradually or rapidly, as may be desired. If the edge of the wheel M is in contact with the periphery of the wheel L 10 at one side of the frame H, the shaft A will be moved from right to left. If the wheel M is then moved to be in contact with the wheel L at the opposite side of the frame H, the motion of the shaft A will be reversed—that is, it will 15 be from left to right. In this manner the motion of the shaft A can be easily reversed by shifting the wheel M, and the machine need not be stopped to reverse the motion. To shift the wheel M, the locking-lever S' is disengaged 20 from the curved notched plate T, and then the arm S is turned the desired distance and turns the arm P, which is connected by the rod or wire d with the fork O, resting in the annular groove in the hub of the friction-wheel M.

25 The great advantage of this device is that the speed and the motion can be changed without stopping the machine, whereby a great loss of power is avoided, and the parts are not subjected to great or sudden strains. The entire 30 mechanism is simple, can be easily operated, and requires but little adjustment.

The above-described mechanism can be used in any machinery, but is best adapted for use with a sawing-machine.

35 Having thus fully described my invention, I claim as new and desire to secure by Letters Patent—

1. The combination of the spring W, rod U, and double nut-frame Y, whereby the belt may 40 be tightened, as described.

2. The combination, with a horizontally-movable friction-wheel, M, of a fixed friction-wheel, L, rotating in contact with and at right angles to it, and provided with a central concavity, a, whereby the wheel M will cease to 45 be actuated as soon as it reaches the concavity a, as and for the purpose specified.

3. In a speed and motion regulator for machinery, the combination, with the shaft A, of 50 the friction-wheel M, mounted thereon, the friction-wheel L, mounted on the shaft journaled in the frame H, pivoted on the shaft A, the shaft of which wheel L is rotated from the shaft from which the power is to be transmitted, and 55 of devices for holding the frame H at the desired inclination, so that the belt which rotates the shaft therein will always be taut, substantially as herein shown and described, and for the purpose set forth.

60 4. In a speed and motion regulator for ma-

chinery, the combination, with the shaft A, of the friction-wheel M, mounted loosely to slide thereon, the wheel L, provided in the middle of its surface with a concavity, a, which wheel L is mounted on the end of a shaft journaled 65 in the frame H, pivoted on the shaft A, substantially as herein shown and described, and for the purpose set forth.

5. In a speed and motion regulator for machinery, the combination, with the shaft A, of the friction-wheel M, mounted loosely thereon, the friction-wheel L, mounted on a shaft journaled in the frame H, pivoted on the shaft A, and of devices for moving the friction-wheel M on the shaft A, substantially as herein shown 70 and described, and for the purpose set forth.

6. In a speed and motion regulator for machinery, the combination, with the shaft A, of the friction-wheel M, mounted loosely thereon, the friction-wheel L, mounted on a shaft journaled in the frame H, pivoted on the shaft A, the fork O, engaging with the hub of the wheel M and sliding on a rod, N, and of a shaft provided with an arm connected with the fork O for moving it parallel with the length of the 80 shaft A, substantially as herein shown and described, and for the purpose set forth.

7. In a speed and motion regulator for machinery, the combination, with the shaft A, of the friction-wheel M, mounted loosely thereon, 90 the friction-wheel L, mounted on a shaft journaled in the frame H, pivoted on the shaft A, the fork O, engaging with the hub of the wheel M and mounted to slide on a rod, N, the arm P of the vertical shaft Q, the connecting-rod 95 d, the handle S, the locking-lever S', and the notched segmental plate T, substantially as herein shown and described, and for the purpose set forth.

8. In a speed and motion regulator for machinery, the combination, with the shaft A, of the friction-wheel M, mounted thereon, the friction-wheel L, mounted on the shaft G, journaled in the frame H, of the spring J, and the adjusting-screw K, substantially as herein 105 shown and described, and for the purpose set forth.

9. In a speed and motion regulator for machinery, the combination, with the shaft A, of the friction-wheel M, mounted thereon, the friction-wheel L, mounted on the shaft G, journaled in the frame H, the rod U, the spring W, the nut-frame Y, and the standard R, substantially as herein shown and described, and for the purpose set forth.

CHRIST ADLER.
